DETERGENT COMPOSITION

Charles Dunbar, Middleton, England, assignor to
Imperial Chemical Industries Limited, a cor-
poration of Great Britain

No Drawing. Application June 23, 1932, Serial
No. 618,937. In Great Britain July 9, 1931

5 Claims. (Cl. 87—5)

This invention relates to detergent composi-
tions and particularly to compositions contain-
ing a compound which comprises a long alkyl
chain and one or more sulfonic groups and a
substance adapted to increase the detergent prop-
erties of such compound.

An object of my invention is to provide new
detergent compositions containing compounds of
the above type in combination with a substance
which increases the detergent properties of the
compounds. A further object is to provide clean-
ing baths for cleansing textiles and textile fibers.
Other objects will appear hereinafter.

These objects may be accomplished according
15 to my invention which comprises admixing a
gelatinous colloidal substance with a compound
containing within its molecule an alkyl chain of
from 16-18 carbon atoms, preferably unsubsti-
20 tuted, and one or more sulfonic groups, to pro-
vide a detergent composition which is adapted to
produce an improved cleansing bath or solution
upon being dissolved in water which cleansing
25 bath or solution is particularly adapted for
cleaning textile materials and particularly wool
and woolen materials.

My invention is based upon my discovery that,
when glue or a similar gelatinous colloidal sub-
stance, such as gelatine or isinglass is added to
30 an aqueous solution of a compound of the above
type, the detergent activity of the solution, is
greatly augmented.

In accordance with my invention, glue or a
similar colloidal substance is incorporated with
35 a detergent compound of the kind described, to
produce an improved scouring or detergent com-
position. The resulting mixture is then dissolved
in water to produce an improved cleansing bath.
However, I do not wish to be limited to such
40 method of manufacturing the cleansing solution
as the glue and the detergent substance may be
added separately or together to the water, with-
out previous admixture, with the production of
satisfactory cleansing solutions or baths.

As suitable long chain detergent substances
45 which may be employed in accordance with my
invention, I may mention: the sodium salt of
cetyl benzyl ether sulfonic acid, the sodium salt
of cetyl sulfoacetate, the sodium salt of octa-
50 decenyl (oleyl) sulfoacetate, the sodium salt of
beta-sulfoethyl oleate.

In order to more clearly illustrate my inven-
tion and the preferred mode in which I contem-
plate carrying the same into effect, the follow-
ing examples are given:

55 Example 1.—A dry composition is made by in-
corporating together, e. g., by milling, 1 part of
the sodium salt of cetyl sulfobenzyl ether and 9
parts of glue.

10 parts of this mixture are dissolved in 1000
parts of water to give a solution possessing a
much more potent scouring action than is shown
by the solution of 1 part of the sodium salt of
cetyl sulfobenzyl ether in 1000 parts of water.

Example 2.—10 parts of glue are added to a
wool scouring bath consisting of 2 parts of the
sodium salt of cetyl sulfoacetate in 1000 parts of
water. The scouring bath shows a surprising in-
crease in scouring efficiency.

While the strict chemical nomenclature has
been employed, it will be understood that the
compounds referred to may be made from com-
mercially available alcohols, i. e., the respective
derivatives may be made from the commercially 15
available cetyl, cleyl, and the like alcohols, or
from alcohols obtainable from sperm oil or by
the reduction of fatty acids and acid mixtures
obtained from other sources and such compounds
may be employed in the crude state as well as 20
in the purified state.

While I have disclosed compositions or clean-
ing baths composed of certain specific com-
pounds, in specific proportions, it will be readily
understood by those skilled in the art that the
compounds and proportions employed may be
widely varied without departing from the spirit
of my invention. Accordingly, the scope of my in-
vention is to be limited solely by the appended
claims construed as broadly as is permissible in
view of the prior art.

I claim:

1. A detergent composition suitable for addi-
tion to cleansing baths for textile fibers compris-
ing substantially the sodium salt of beta-sulfo-
ethyl oleate, and glue.

2. A detergent composition suitable for addi-
tion to cleansing baths for textile fibers compris-
ing substantially the sodium salt of cetyl sulfo-
benzyl ether, and glue.

3. A dry composition suitable for addition to
cleansing baths for textile fibers comprising sub-
stantially about one part of the sodium salt of
cetyl sulfobenzyl ether, and about nine parts of
glue.

4. A detergent composition for textile fibers
comprising a compound selected from the group
consisting of the alkali-metal salts of cetyl-sulfo-
benzyl ether, cetyl-sulfo-acetate, octadecenyl-
sulfoacetate and beta-sulfoethyl-oleate, and a
protective colloid selected from the group con-
sisting of glue, gelatine and isinglass.

5. A cleansing bath for textile fiber compris-
ing an aqueous solution of a composition as de-
fined in claim 4.

CHARLES DUNBAR.
